(57) **CLAIM**

The ornamental design for an angular indicator tool, as shown and described.

DESCRIPTION

FIG. 1 is a top perspective view of the angular indicator tool; FIG. 2 is a bottom perspective view of the angular indicator tool of FIG. 1;

FIG. 3 is a front elevation of the angular indicator tool of FIG. 1;

FIG. 4 is a rear elevation of the angular indicator tool of FIG. 1;

FIG. 5 is a right-side elevation of the angular indicator tool of FIG. 1;

FIG. 6 is a left-side elevation of the angular indicator tool of FIG. 1;

FIG. 7 is a top view of the angular indicator tool of FIG. 1; and,

FIG. 8 is a bottom view of the angular indicator tool of FIG. 1.

The phantom lines are provided for illustrative purposes only and form no part of the claimed design.
